W. ARKIN.

ARTIFICIAL TOOTH.

APPLICATION FILED JUNE 23, 1919.

1,335,717.

Patented Apr. 6, 1920.

Inventor:
William Arkin,
By his Attorney,
Geo. W. Math

UNITED STATES PATENT OFFICE.

WILLIAM ARKIN, OF NEW YORK, N. Y.

ARTIFICIAL TOOTH.

1,335,717.

Specification of Letters Patent.

Patented Apr. 6, 1920.

Application filed June 23, 1919. Serial No. 306,253.

To all whom it may concern:

Be it known that I, WILLIAM ARKIN, a citizen of the United States, and a resident of the borough of Bronx, county of Bronx, 5 city and State of New York, have invented certain new and useful Improvements in Artificial Teeth, of which the following is a specification.

My invention relates to what are known 10 in the art of dentistry as "detachable" teeth in which provision is made for detachably securing a porcelain or other artificial tooth facing to a base, bridge, crown or other support in such manner that a new front or 15 tooth facing may be substituted for one that is worn or broken without the destruction or injury of the base or support.

The objects of my invention are to afford copulative means of simplicity and 20 strength, and to standardize both base and facing in such manner that they may be manufactured as stock articles of given sizes and shapes so that the practising dentist may purchase them as required for use.

25 The invention consists in the specific construction and arrangement of parts described and claimed, distinctive features being the undercutting or dovetailing of the socket in the tooth facing and the truing up 30 of the back of such facing to insure conformity to the standardized metallic base or backing or support, all as hereinafter more fully set forth.

In the accompanying drawings,

35 Figure 1, is a rear view of the tooth facing; Fig. 2, a side elevation thereof;

Fig. 3, is a section taken upon plane of line 3—3, Fig. 1;

Fig. 4, is a side elevation of the tooth 40 facing applied to the metallic base;

Fig. 5, is a section of the parts shown in Fig. 4, and taken upon plane of line 3—3, Fig. 1;

Fig. 6, is a rear elevation of the metallic 45 base;

Fig. 7, is an elevation of the inner face thereof;

Fig. 8, is an edge view of the metallic base;

50 Fig. 9, is a section taken upon plane of line 9—9, Fig. 7;

Fig. 10, is a rear elevation of a tooth facing showing a modification in the form of the socket;

Fig. 11, is a view of the inner side of a metallic base adapted for engagement with the tooth facing shown in Fig. 10;

Fig. 12, is a rear elevation of a tooth facing showing another modification in the form of socket;

Fig. 13, is a view of the inner side of a metallic base adapted for engagement with the tooth facing shown in Fig. 12;

Fig. 14, is a rear view of a tooth facing showing still another modification in the form of socket;

Fig. 15, is a view of the inner side of a metallic base adapted for engagement with the tooth facing shown in Fig. 14.

The metallic base B, may be formed by 70 means of dies or otherwise as may be found most expedient. It is adapted to be incorporated in bridge work or reinforced by a metallic backing as solder as indicated by the dotted lines b, Fig. 5, in a manner well 75 known in the art.

The inner face b', of the base is absolutely true in the sense that, except for the recess b², it extends in a single flat plane. The recess b², is formed for the accommodation of 80 the protuberant side walls f of the tooth facing F, as shown more particularly in Fig. 5, of the drawings. b³, is a stud integral with the base B, and preferably centralized in position in the recess b². It is also preferably of such length as to protrude beyond 85 the inner surface b', of the base B, so as to project well into the socket f', when the tooth facing F, is applied to the base B, as in Fig. 5.

90 The configuration of the recess b², and the socket f', is not material provided they conform to each other. That is to say, the protuberant side walls f, of the socket f', of the facing must fit snugly within the inner side 95 walls of the recess b², in the metallic base as shown in Fig. 5, and this applies whatever the configuration of socket and recess may be. Thus in the first nine figures of the drawing I show both recess b², and socket 100 walls f, as in the form of an oblong square, while in the remaining figures, 10 to 15 inclusive, various configurations of recess b², and socket side walls f, are shown, the same function being involved in all,—i. e., that of 105 affording lateral support for the tooth facing on all sides. This support is supplemented and reinforced by the stud b³, of the

base, which stud is embedded in the cement *c*, introduced into the socket *f'*, of the tooth facing *F*, as in Fig. 5.

In order that this cement *c*, may act as 5 an anchor and positive coupling for and between the parts, I undercut or dovetail the socket *f'*, as shown in Figs. 3 and 5, or substantially so, in such manner that the base of the cement *c*, will extend laterally beyond 10 the mouth of said socket and hence maintain a firm hold upon, and in fact become an integral part of, the tooth facing.

The undercutting or dovetailing of the bottom of the socket *f'*, may be accomplished 15 in various ways during the making of the porcelain facing *F*, and preferably extends under the side walls *f*, all around the socket, although this is not absolutely essential as any undercutting or widening of the bottom 20 of the socket as related to the mouth and protuberant side walls *f*, thereof will tend to render more positive the jointure of parts.

In order to strengthen the union between the stud *b*³, and the cement *c*, said stud may 25 be corrugated or serrated as shown by way of illustration in Fig. 9, thus augmenting frictional contact and resistance and tending to preserve the integrity of the coupling.

The rear surfaces of the tooth facing *F*, 30 contacting with the base *B*, are trued or finished off with accuracy to fit snugly the opposed surface *b'*, of the base and the inner side walls of the recess *b*². By this means the standardizing of the parts is attained so 35 that they may be manufactured separately and carried in stock,—being properly graded as to size and shape,—so that a practising

dentist can order and procure the parts as wanted. Thus in the case of the breaking or disfigurement of a tooth facing *F*, the dentist can order a duplicate for substitution and replacement, knowing that the same will fit the backing *B*, equally as well as the original facing. 40

What I claim as my invention and desire 45 to secure by Letters Patent is:

1. An artificial tooth of the character designated, comprising a facing formed with an undercut protuberant socket, a metallic base formed with a recess coincident 50 with said facing socket, and with a stud protruding into said facing socket, and a cement filling positioned in said undercut facing socket and in said recess in the base and around said base stud to form coupling means between said base and said facing, for the purpose described.

2. An artificial tooth of the character designated, comprising a facing formed with an undercut socket having protuberant side 60 walls, a metallic base formed with a recess coincident with said facing socket and fitting the protuberant side walls thereof and also formed with a stud protruding into said facing socket, and a cement filling positioned in said undercut facing socket and in said recess in the base and around said base stud to form coupling means between 65 said base and said facing, for the purpose described.

WILLIAM ARKIN.
